SPARK PLUG

Cecil R. Benton, Vergennes, Vt.

Application June 15, 1936, Serial No. 85,201

3 Claims. (Cl. 123—169)

The invention relates to spark plugs.

The primary object of the invention is to provide an electrode on the shell of the plug, usually the "ground" electrode which can be readily and accurately deformed or varied to provide the optimum gap for sparking and also shields the sparking face on the center electrode from direct contact with the flame in the cylinder.

Another object of the invention is to achieve this primary object with a diversity of forms of electrodes, and with spark plugs for engines having different output characteristics.

Other objects of the invention will appear from the detailed description.

15 The invention consists in the several novel features which are hereinafter set forth and are more particularly defined by claims at the conclusion hereof.

In the drawing:

20 Fig. 1 is a longitudinal section of a spark plug embodying one form of the invention;

Fig. 2 is a section, on an enlarged scale, through the electrodes and shell, illustrating the manner of resetting the electrode on the shell to vary, and provide the optimum gap between the sparking faces of the electrodes;

Fig. 3 is an end view of the plug illustrated in Fig. 1;

Fig. 4 is a section illustrating a modified form 70 of the invention applied to a center electrode used for a high output engine;

Fig. 5 is an end view of the plug illustrated in Fig. 4;

Fig. 6 is an end view embodying another modified form of the outer electrode.

The invention is exemplified in Figs. 1 to 3 in a spark plug comprising a shell 10, which is provided with the usual screw-thread for engaging a corresponding internal thread in the engine casting and with a polygonal flange 11 whereby the assembled plug may be screwed into the casing; a center electrode 12 having a cylindrical terminal 13 at its inner end on which the flat circular sparking face 14 is formed; and a stem 9 extending longitudinally through the plug; a sleeve 15 of suitable insulation surrounding the stem 9 and engaged by a shoulder 16 on electrode 12; a coupling ring 17 provided with a screw-thread 18 for engaging a corresponding internal thread in the shell 10 and having a shouldered inner end for engaging a gasket 20 and forcing it against a conoidal surface in the shell; a collar 21 fixed to the outer end of the stem 9 of electrode 12 and for electrical connection with a conductor wire;

and a sleeve 22 of insulation between collar 21 and ring 17.

The ground contact 24 consists of a strip of metal extending across the cylindrical opening in the inner end of shell 10, with its ends 25 seated in recesses cut in the end of the shell and secured therein by brazing or welding, as indicated at 26. The central portion 27 of the strip 24 is offset longitudinally of the axis of the inner electrode 12, being bent as at 28 between the portions 25 and 27. The inner face of offset portion 27 forms the sparking face of the ground electrode. The electrode 24 is shaped from a strip of flat stock and its central portion 27 is of sufficient width or area to overlie the sparking face 14 on the central electrode 12 so it will shield the sparking face 14 of the central electrode from the flame in the cylinder and prevent scouring of the sparking face 14 by such flame. The central electrode 12 is usually made of a spark-resisting alloy of 20 steel, because it is insulated from the shell and is thus not as well cooled by intimate contact with the cylinder head. The electrode 24 is formed of a metal, steel or alloy which is sufficiently ductile or malleable so as to avoid any spring-action 25 when it is deformed and so that when it is impacted by a tool, such as a suitable hammer, the central portion 27 will remain set in its deformed shape with practically no tendency to spring back to its normal shape. This degree of ductility 30 or malleability may be attained by subjecting the metal to suitable heat treatment. The heat applied to the ends 25 of the strip, for welding or brazing them to the shell, may be utilized to some extent for this purpose. The ground electrode 35 may be made of spark-resisting alloy, since it can be separately formed from the shell or integrally formed therewith. In either event, the material should be sufficiently ductile or malleable to eliminate any spring-action when it is deformed, compressed or bent, and to cause it to remain set in its adjusted position or shape.

When the gap between the sparking surfaces on the electrodes becomes excessive from use or wear, an ordinary hammer of suitable size may be 45 used to pound down the portion 27 of the strip forming the electrode 24. A templet or strip *a*, indicated by dotted lines in Fig. 2, of a correct thickness to correspond to the optimum gap between the electrodes, may be inserted between 50 them while the portion 27 of the strip forming electrode 24 is hammered down to provide the proper gap. On account of the softness or lack of spring in the metal forming the electrode 24, the central portion 27 will be set, as indicated 55

by dotted lines in Fig. 2, so that the sparking face on its inner side will be brought down to the correct distance from the sparking face of the center electrode, without resulting in any substantial recession of the sparking face on portion 27 from the strip *a* or the sparking face 14 of the inner center electrode. By hammering down the entire central portion 27 and the use of a templet, the normal parallelism of the sparking-faces, 10 which are perpendicular to the axis of the electrode 12, will be retained. By forming the ground electrode of metal which will remain set in the position in which it is hammered, it makes it possible to provide a spark plug in which the sparking 15 face of the center electrode is shielded by the ground electrode to prevent direct contact of the flame with the sparking face of the inner electrode and to easily vary or adjust the sparking faces for the correct or most efficient spark gap.

20 In the event that the gap between the sparking faces of the electrodes is too small, after the electrode 24 has been applied, the gap may be increased by screwing out the assembly consisting of the electrode 12, sleeves 15, 22 and ring 17 25 slightly, inserting a templet *a* and then screwing down the said assembly. Usually, use of the plug increases the gap and the adjustment required is a decrease of the gap, which is done by hammering the portion 27 of electrode 24, as before described.

30 In low output engines, the diameter of the cylindrical end 13 of the inner electrode is smaller than the diameter used in high output engines. In the modification illustrated in Figs. 4 and 5, the electrode 24^a on the shell is made of metal 35 having the ductile and springless properties hereinbefore described and comprises a central portion 27^a of sufficient area to extend over the sparking face on the large cylindrical end 13^a of the central electrode 12^a of a spark plug for a high 40 output engine. The ends 25^a of the strip 24^a are brazed or welded in recesses in the end of the shell 10^a. In this modification the electrode 24^a is normally flat and its entire flat central portion is adapted to be deflected or hammered toward the 45 sparking face 14^a of the inner electrode, as indicated by dotted lines in Fig. 4, so as to maintain parallelism between the sparking surfaces. In high output engines, it is desired to terminate the central electrode inwardly of the end of the shell 50 as shown. In this case, the central portion 22^a is deflected downwardly by a suitable hammer to keep its inner face in parallelism with the sparking face 14^a and the metal between the central portion and the end portions 25 is deflected downwardly and stretched, as indicated at 28^a. While 55 this is done a templet may be inserted between the sparking faces of the electrodes to arrest and set the central portion of the strip the correct distance from the sparking face 14^a and provide 60 the correct spark gap.

Fig. 6 illustrates a modified form of ground electrode of ductile or malleable metal having the same properties as those hereinbefore described and which comprises a circumferential rim 30 65 which is brazed or welded, as indicated at 31, to the shell 10^b; a central portion 32 adapted to extend over and shield the sparking face on the end of the inner electrode 12^b, and a series of connecting arms 33 between the annular portion 70 30 and the central portion 31. The central portion 32 may be deflected by a hammer, as hereinbefore described, when the sparking faces are to be brought together to compensate for wear. In this form of the invention the arms 33 are offset 75 adjacent the annular portion 30 to permit the

deformation of the metal while the central portion is being hammered to form the desired spark-gap.

The invention exemplifies a spark plug with an electrode on the shell which shields the sparking face of the central electrode from direct contact with the cylinder flame and is readily and accurately variable to provide the optimum spark-gap. The invention also provides for variation of the spark-gap by hammering, which results in resetting or adjusting the metal without spring-action. The invention also provides for embodying these features in ground electrodes of different forms. The invention also provides a ground electrode having these characteristics which provide for 15 recession of the spark-plug gap into the shell for high output engines.

The invention also provides a ground electrode having these characteristics which may be separately formed from the shell, so that they may be 20 made of spark-resisting metal, although it is to be understood that in some instances the invention may be applied to ground electrodes which, for cheapness in manufacture, are integrally formed with the shell.

The invention is not to be understood as restricted to the details set forth, since these may be modified within the scope of the appended claims, without departing from the spirit and scope of the invention.

Having thus described the invention, what I claim as new and desire to secure by Letters Patent is:

1. A spark plug comprising a shell provided with means whereby it may be secured to an engine-casing, an inner electrode in the shell having a flat sparking-face at its inner end, and a flat strip forming a coacting electrode, bridging the inner end of the shell, formed separately from and having both of its ends permanently bonded to the shell and comprising an integral central portion having a substantially flat sparking-face parallel with the sparking-face on the inner electrode, said strip being formed of malleable or ductile metal which can be pounded or deflected toward the sparking-face on the inner electrode to vary the gap between the sparking-faces by deformation between its central portion and both of its bonded ends, so that the central portion will remain set and maintain the parallelism between the 50 sparking-faces.

2. A spark plug comprising a shell provided with means whereby it may be secured to an engine-casing, an inner electrode in the shell having a flat sparking-face at its inner end, and a flat strip forming a coacting electrode, bridging the inner end of the shell, formed separately from, and having both of its ends permanently bonded to the shell and comprising an integral central portion having a substantially flat sparking-face 60 parallel with the sparking-face on the inner electrode and longitudinally extending portions between the central portion and the bonded portion, said strip being formed of malleable or ductile metal which can be pounded or deflected toward 65 the sparking-face on the inner electrode to vary the gap between the sparking-faces by deformations in the longitudinally extending portions, so that the central portion will remain set and maintain the parallelism between the 70 sparking-faces.

3. A spark plug comprising a shell provided with means whereby it may be secured to an engine-casing, an inner electrode in, and terminating inwardly of, the shell having a flat 75 sparking-face at its inner end, and a transversely 75

straight flat strip forming a coating electrode, bridging the inner end of the shell, formed separately from and having both of its ends permanently bonded to the shell and comprising an integral central portion having a substantially flat sparking-face parallel with the sparking-face on the inner electrode, said strip being formed of malleable or ductile metal which can be pounded

or deflected toward the sparking-face on the inner electrode to vary the gap between the sparking-faces by deformations between its central portion and both of its bonded ends, so that the central portion will remain set and maintain the parallelism between the sparking-faces.
